METHOD OF KNITTING FABRIC WITH
ELASTIC INLAY AND EMBROIDERY PAT-
TERN

James L. Getaz, Maryville, Tenn.

Application March 12, 1938, Serial No. 195,634

10 Claims.

(Cl. 66—9)

This invention relates to knit fabrics and more particularly to method of knitting fabrics and it is an object of this invention to provide a method of knitting fabric having an elastic thread laid in the fabric and embroidery yarns knit at selected wales in courses of the fabric.

In the drawings:

Fig. 1 is a plan view of a portion of a fabric knit in accordance with this invention, the fabric being expanded, and showing the relations of the various threads of which the fabric is formed, one of the threads being shown as a wrap thread;

Figure 2 is a view similar to Figure 1 but showing a thread knit as a mock wrap thread in place of the wrap thread as in Figure 1;

Fig. 3 is a diagrammatic view in elevation showing the relations of the needles and cams in the knitting of the fabric of Fig. 2; and

Figure 4 is a view similar to Figure 3 showing the relations of the needles and cams in the knitting of the fabric of Figure 1.

In Figure 1 of the drawings, there is shown, in expanded condition, a number of courses, as courses *a* to *q*, and a number of wales, as wales 1 to 11, of a fabric knit in accordance with this invention. Throughout the portion of the fabric shown the main or body yarn *B* is knitted by every needle in each course and the rubber or elastic thread *R* is fed in each course in front of and below the latches of alternate or recurrent needles, as the needles which knit the wales 1, 3, 5, 7, 9, 11 etc., the rubber thread being cast off with the loops of the body yarn at the usual knitting wave, an operation which causes the rubber thread to be engaged between the sinker and needle loops of the wales 2, 4, 6, 8, 10 etc.

On selected ones of the needles in front of which the rubber thread *R* is placed the embroidery yarn *E* is wrapped. As shown in Figure 1, in which a genuine wrap is illustrated, the embroidery yarn is wrapped upon the same needle, the needle of wale 9, for two successive courses, as courses *b* and *c*, and then in the following course *d* wrapped upon an adjacent needle in front of which the rubber thread is placed at either side of the needle previously taking the wrap yarn, as the needle of wale 7. This gives an embroidery stripe having two stitches of the embroidery yarn in a wale and then two stitches of the embroidery yarn in a wale spaced from the previous embroidered wale by an intervening wale. A fabric having rubber laid in the manner described is, when contracted, substantially a flat fabric in which the wales knit by

the needles in front of which the rubber thread is laid are forced to the face of the fabric while the wales knit by the intervening needles in back of which the rubber thread is floated are forced to the back of the fabric. This results in providing a flat fabric in which the embroidered wales lie adjacent to each other when the fabric is in the contracted condition and gives the appearance of a continuous embroidery pattern on a rib fabric although the embroidery stitches are separated by an intervening wale and are spaced apart when the fabric is in an expanded condition. As the fabric is expanded to some extent as knit, the floats of the embroidery yarn are of sufficient length to permit expansion of the fabric. While Figure 1 shows but a single wrap yarn and that yarn wrapped upon but a single needle in a course, it is to be understood that a plurality of wrap yarns may be used with some of the yarns being taken by a plurality of selected needles in the usual way.

Where the embroidery thread is fed at the throat plate to form a mock wrap embroidery pattern the rubber thread may be fed to spaced courses only, if desired, and still kept a continuous thread without entangling with the floats of the embroidery thread provided the embroidery thread is taken by needles at a number of places about the needle circle to knit what is known as an "all over" pattern as the short floats of the embroidery yarn then lie close to the fabric and do not cause loops of objectionable size to be formed of the rubber thread float. Where a mock wrap pattern is formed at spaced points, as at opposite sides of the stocking, it is necessary to feed the rubber thread in each course in which the embroidery thread is fed to the needles; but, if the rubber thread is fed at each course it is not necessary to feed the embroidery thread in each course. Where the embroidery thread is fed to form a mock wrap the rubber thread will be placed in front of alternate needles and the embroidery threads will be taken by selected ones of such alternate needles as when the embroidery thread is fed to form a genuine wrap pattern. In Figure 2 there is shown, in extended condition, a fragment of a fabric in which the mock wrap yarn *M* is used in place of the wrap yarn of Figure 1. In this fabric the body yarn *B* is knit at all wales in each course of the courses *a*' to *e*' shown and the elastic thread *R* is engaged at alternate wales in each course while the mock wrap yarn is shown engaged at selected wales in spaced courses, the long float of the mock wrap yarn is shown as severed in the

course *c'*. The mock wrap yarn may be taken by a group of successive needles as shown in the course *a'*.

In Figs. 3 and 4 there is shown an arrangement of needles and cams of a circular knitting machine for knitting the fabrics described and shown in Figs. 1 and 2. In this arrangement jacks **381** are mounted in the grooves of the needle cylinder below the needles. There is also provided an auxiliary pattern drum, (not shown) which operates the reader cams **765** for effecting a selection of the jacks for operation by the cam **366'** to raise selected needles to take the wrap yarns, if the wrap yarns **E** be fed by wrap yarn guides **767** in advance of the throat plate as in Fig. 4, or to take the mock wrap yarns **M** if these yarns be fed at the throat plate as in Fig. 3.

In the operation of the machine to knit fabric in accordance with this invention, the alternate needles **21** are raised by the engagement of their jacks **381** with the cam **366** in advance of the yarn guide **30** which lays the elastic thread **R** against the shanks of the raised needles **21** and below the latches thereof. The needles **22** are then raised by a cam **33** to a level slightly below the level of the needles **21** and as the needles **22** are raised the shape of the top of their hooks causes the elastic thread to pass to the back of the needles **22** so that the elastic thread is interlaced with the needles. All needles are then brought down to the same level by the cam **34** but not low enough to cast off the loops on the needles. While the needles are being raised by the cam **33**, a cam **35** engages the upper portions of the jacks **381** causing the lower ends of the jacks to be moved outwardly to a position in which their butts pass without engaging the cam **366'** and only those jacks having butts engaged by the reader cams **765** will be engaged by the cam **366'** and raised to position their needles to take the embroidery yarns. Such needles as are not raised by their jacks **381** engaging the cam **366'** are raised by the cam **40** to a position insuring the clearing of their latches.

In Fig. 3 the cams and yarn guides are shown arranged to feed the embroidery yarn **M** at the throat plate to form a mock wrap. In this case the yarn guide **F⁵** feeding the embroidery yarn is at the right side of the throat plate, as seen in Fig. 3, and positioned to feed the yarn at a higher point than the yarn guide **F¹** for the body yarn **B** which is at the left side of the throat plate and lower. This arrangement of the yarn guides places the embroidery yarn where it will be taken by the needles which are raised by the engagement of their jacks on the cam **366'** but will not be taken by the needles whose jacks are not raised by the cam **366'**. For this operation the right hand stitch cam (not shown) is withdrawn and a narrower center stitch cam **357** is used. All the needles engage the cam **357** and are drawn down by the cams **357** and **360**, taking the body yarn **B** and drawing loops of both yarns **B** and **M** and casting off the loops previously taken and the lengths of the elastic thread engaging alternate needles.

As shown in Fig. 4 when making the genuine wrap fabric and the raised needles are wrapped by the embroidery yarn **E**, the wrap yarn guides **767** are operated to place the embroidery yarns about the selected needles after these needles have been raised by the engaging of their jacks with the cam **366'** and before the throat plate is reached by the needles which take the wrap yarns. In this case the usual stitch cams can be used.

After the selected jacks have been raised by the cam **366'** a cam **36** engages the lower portions thereof to position the jacks for operation by the cam **366**.

Where, in the claims, reference is made to courses with elastic thread therein adjacent to courses with embroidery yarn therein "adjacent" is not to be limited to placing the elastic thread in the next course to the course with the embroidery yarn but as being within a few courses and being sufficiently close that the contraction of the elastic thread effects a contraction of the fabric at the embroidery pattern.

This application is a continuation in part of my co-pending application Serial No. 61,612, filed January 30, 1936.

I claim—

1. Steps in a method of knitting a course of a fabric comprising raising alternate cylinder needles of a circular knitting machine in advance of the usual knitting wave, feeding a rubber thread in front of and below the latches of the raised needles and in back of the intermediate needles, feeding embroidery yarns to selected needles and operating all needles to take the main or body yarn or yarns and to cast off.

2. Steps in a method of knitting a course of a fabric comprising raising alternate cylinder needles of a circular knitting machine in advance of the usual knitting wave, feeding an elastic thread in front of and below the latches of said raised needles, raising the remaining needles to interlace the elastic thread with the needles, lowering all needles, raising selected needles to take an embroidery yarn and operating all needles to take the body yarn and to cast off.

3. Steps in a method of knitting a course of a fabric comprising operating the cylinder needles of a circular knitting machine to interlace an elastic thread therewith, operating selected needles to take embroidery yarn and operating all needles to take the body yarn and to cast off.

4. Steps in a method of knitting a fabric comprising raising selected cylinder needles of a circular knitting machine, laying an elastic thread against said selected needles, operating the cylinder needles to interlace the elastic thread therewith, operating selected ones of the previously selected needles to take embroidery yarn and operating all cylinder needles to take the body yarn and to knit the body and embroidery yarns and cast off the elastic thread.

5. Steps in a method of knitting a fabric comprising raising selected cylinder needles of a circular knitting machine, feeding an elastic thread to said selected needles, raising the remaining cylinder needles to interlace the elastic thread therewith, operating selected needles to take embroidery yarn and operating all needles to take the body yarn and to knit the body and embroidery yarns and cast off the elastic thread.

6. Steps in a method of knitting an embroidered plain fabric portion comprising knitting courses of main or body yarn or yarns, selecting needles to engage embroidery yarn during the knitting of courses of said fabric and engaging elastic thread at recurring needles in the knitting of courses adjacent embroidered courses.

7. Steps in a method of knitting an embroidered plain fabric portion comprising knitting courses of main or body yarn or yarns, selecting needles to engage embroidery yarn during the knitting of courses of said fabric and engaging an elastic thread at spaced recurring needles in the knitting of courses adjacent embroidered courses.

8. Steps in a method of knitting an embroidered plain fabric portion comprising knitting courses of main or body yarn or yarns, selecting needles to engage embroidery yarn during the knitting of courses of said fabric and engaging an elastic thread at spaced recurring needles in the knitting of courses between embroidered courses.

9. Steps in a method of knitting an embroidered plain fabric portion comprising engaging in-
10 elastic yarn with the needles in knitting courses of said fabric, engaging an elastic thread at selected needles in certain courses of said fabric

and selecting needles to engage embroidery yarn during the knitting of courses of said fabric adjacent to said elastic thread.

10. Steps in a method of knitting an embroi-
dered plain fabric portion comprising engaging inelastic yarn with all the needles in knitting 5 courses of said fabric, engaging an elastic thread at spaced selected needles in knitting courses of said fabric and selecting needles to engage em-
broidery yarn during the knitting of courses 10 of said fabric adjacent to said elastic thread.
